INVENTOR,
C. A. Henry
BY
Howard S. Smith
ATTORNEY

UNITED STATES PATENT OFFICE

CASELY A. HENRY, OF DAYTON, OHIO

CAN OPENER

Application filed April 5, 1930. Serial No. 441,800.

This invention relates to new and useful improvements in can openers.

It is the principal object of my invention to provide a simple and efficient device which embodies the features of a can opener, a fruit jar wrench and a bottle opener.

It is another object of my invention to so construct the device that it can be adjusted to fit the top of any size can or jar.

10 Still another object of my invention is to use ground steel for the cutting edge of my device, so that when a pressure is exerted, this edge will cut into the tin can, turning down the edges and thereby leaving the cut edge free from rough places and snags.

My adjustable can opener and fruit jar wrench may be economically constructed from steel, or any other light metal, for sale at a reasonable price.

20 Other important and incidental objects will be brought out in the following specification and particularly set forth in the subjoined claims.

In the accompanying drawings illustrating my invention Figure 1 is a perspective view of my improved can opener showing the starting of the cutting operation. Figure 2 is a side view of my device used as an adjustable jar wrench. Figure 3 is a plan view of the body part of the can opener, and Figure 4 is a side view, partly in section, showing the means for connecting the handle to the body part of the can opener.

Referring to the accompanying drawings 35 for a detailed description of my invention the numeral 1 designates the body portion of my can opener, which is preferably stamped from a steel blank and provided with a ground steel cutting edge 2 which tapers to a central point 3. Formed at the middle point of the straight edge of the blank 1 is a lip 4.

Provided near the top of the body portion 45 are two internal racks 5 which are the adjusting means for my device. The rack teeth are on opposite sides of the slots. One rack 5 is in an inverted while the other is in an upright position.

The blank 1 is bent around a center line α 50 extending from the point 3 to the aperture 4*

in the lip 4, to form the curved body shown in Figures 1 and 2.

A handle 6 is then attached to the body portion of the can opener by extending the handle through the gear teeth slots until the 55 rack teeth mesh with gear teeth 7 formed on a stud 8 in the inner end of the handle. When this connection is completed a washer 9, a nut 10, and lock nut 11 are secured on the stud 8 for the purpose of holding the handle 60 securely in place.

By a slight turn to the right the gear teeth 7 will mesh with the rack teeth 5 and cause the body portion of the can opener to contract, whereas, a slight turn to the left will 65 result in the expansion of the opener.

When the cutter is adjusted to fit the can to be opened, a slight pressure upon the lip 4 will cause the point 3 of the steel cutting edge 2 to puncture the can thereby starting 70 the cutting operation. As the pressure is increased the severing operation is continued, turning down as it proceeds the cut edge of the can, until the entire top is severed and ready for removal. (Figure 1.)

75 By inverting my device, as shown in Figure 2, I provide a jar wrench. The opener is placed in an inverted position on the jar and by a turning movement of the handle 6, the device is tightened by means of the internal racks 5. When thoroughly tightened around the lid, a sharp twist of the opener 80 will loosen the lid of the jar and it can then be easily removed.

To increase the uses of my device, I have 85 provided the handle 6 with a recessed part 13 to engage and remove the cap from a bottle.

It is thus obvious that in addition to its use as a can opener, my device may be employed to successfully remove jar lids and 90 bottle caps.

Having described my invention, I claim:

1. A can opener comprising a triangular bowed or folded blank having a base edge 95 defining a plane and two cutting edges that meet in the apex of the blank, two internal rack portions, one on each side of the center line of the blank and parallel with its base edge, the teeth of one rack portion facing the 100

- base edge and the teeth of the other rack portion facing in the opposite direction, a handle, and gear teeth on said handle adapted to engage the teeth of said internal racks when the blank is folded to bring the rack portions over each other for the purpose specified.
2. A can opener comprising a triangular bowed or folded blank having a base edge defining a plane and two cutting edges that meet in the apex of the blank, said blank formed with two rack slots, one on each side of the center line of the blank and parallel with its base edge, the teeth in one rack slot facing the base edge and the teeth of the other rack slot facing in the opposite direction, a handle, a projection on the inner end of the handle, gear teeth formed on said projection to engage the rack teeth when the blank is folded to bring the rack slots over each other, and means applied to the projection on the handle, beyond the gear teeth, to hold the latter securely in the rack slots for the purpose specified.
- 25 3. A can opener comprising a triangular bowed or folded blank having a base edge defining a plane and two cutting edges that meet in the apex of the blank, a lip formed on the middle portion of its base edge part, said blank also formed with two rack slots, one on each side of the center line of the blank and parallel with its base edge, the teeth in one rack slot facing the base edge and the teeth in the other rack slot facing in the opposite direction, a handle, and gear teeth formed on said handle adapted to engage the teeth of said internal racks opposite the lip when the blank is folded to bring the rack slots over each other, for the purpose specified.
- 40 4. A combination can opener and jar lid remover, comprising a triangular bowed or folded blank having a base edge defining a plane and two cutting edges that meet in the apex of the blank, said blank formed with two rack slots, one on each side of the center line of the blank and parallel with its base edge, the teeth in one rack slot facing the base edge and the teeth of the other rack slot facing in the opposite direction, said blank adapted to be folded around a jar lid or held in a reverse position to present its apex end to the top of a can, a handle, and gear teeth on the handle adapted to engage the rack teeth in either position of the folded blank, for the purpose specified.

In testimony whereof I have hereunto set my hand this 1st day of April, 1930.

CASHLY A. HENRY.
